UNITED STATES PATENT OFFICE.

HEINRICH BIEMER, OF BERLIN, GERMANY.

PADLOCK.

Application filed March 18, 1922, Serial No. 544,799, and in Germany May 7, 1921.

The padlock according to the invention offers a great security against an unauthorized opening by arranging a turnable lock cylinder within the bore of a solid metal piece. The lock cylinder is provided with a crown having inclined faces by means of which upon its being turned a bolt is moved for locking the bow. A pin within the lock cylinder serves as a tumbler which engages with a recess in the wall of the bore in the solid metal piece and which leaves this recess only if with its one end it fits exactly the notch of a pin which can be moved vertically to it by means of the key.

Upon the drawing one mode of carrying out the invention is shewn and it is:

Fig. 1, a section through the padlock according to the invention,

Fig. 2, a section along the line A—A of Fig. 1,

Fig. 3, a view of the piece carrying the bolt,

Fig. 4, a plan and a partial side view of the crown of the lock cylinder,

Fig. 5, a view of one of the locking sleeves, and

Fig. 6, the view of a key for such a lock.

The body of the padlock which may be made of any suitable metal is denoted by *a*, while *b* represents the bow. The bow is provided with a channel *b*¹, in which a spiral spring is arranged. The spiral spring is at the opening of the channel suitably provided with a pin or with a small cylindrical body. This spring serves the purpose to push the bow upwards when the lock has been opened. The bow is further provided with a horizontal groove *b*² and following the latter with a vertical groove *b*³. At the end of this groove a pin *c* has been inserted into the body of the lock which serves to guide the bow after it has been unlocked. A port *d* has been drilled into the body *a* of the lock. Into this port are placed a cylindrical body *f*, a lock cylinder *g* and two closing sleeves *h* and *i*. The cylinder *f* possesses two bores *f*¹ and *f*² which are connected with each other by a passage *f*³, see Fig. 3. Within the bore *f*² there is the bolt *f*⁴ to which a little rod *f*⁵ has been attached. A spiral spring *f*⁶ tends to push the bolt into the opened position.

The lock cylinder *g* is on the side facing the bolt *f*⁴ fitted with notches *g*¹, see Fig. 4. These notches have inclined faces *g*², while at *g*³ they are each provided with a

wall vertical to the axis of the cylinder. The notches *g*⁴ are fitted in the same manner but on a much smaller scale. Upon a turning of the cylinder *g* the notches *g*¹ push the bolt *f*⁴ into its final position, while the small notches *g*⁴ keep it arrested in this position. The bolt *f*⁴ is chamfered on the side facing the crown according to the faces *g*². In the cylinder *g* slideable in a port *g*⁵ therein is a pin *k* having a notch *k*¹ and a spiral spring *l*. The pin *k* is by means of any suitable device secured against a turning about its longitudinal axis. Accurately matching the roof shaped walls of this notch, the upper end of a further pin *m* in a port *g*⁶ has been shaped accordingly. A spring *m*² forces this pin against the pin *k*. On two sides of the port *d* opposite to each other two bores *a*¹ have been provided for. Into these the pin *m* can enter and thereby prevent a turning of the cylinder *g* and thus an opening of the lock. Only when the pin *k* is accurately pushed back to such an extent that the point of pin *m* fits exactly the notch *k*¹ will the pin *m* leave the bore *a*¹ and can the lock be opened.

The cylinder *g* is furthermore fitted with an extension *q*⁵ which serves to prevent a skeleton key or another instrument from engaging the pin *k*.

There are furthermore two closing sleeves *h* and *i* in the port *d* where they are fastened by means of the screws *n* and *o*. As such may be seen from Fig. 5, the sleeves *h* are on their plate shaped side provided with notches *p* for allowing the key to pass through. The key (Fig. 6) consists of a flat metal strip having on its edges notches *q*¹ and *q*². Of the cut out ends of the key the section *q* serves to move the pin *k* while the section *r* fits into a notch *q*⁶ of the cylinder *g* and enables a turning of this crown by means of the key. The section *r* can be recessed in any manner at *r*¹ so that it fits into the hole *q*⁶ shaped accordingly.

Having now fully described and ascertained the nature of my said invention, and the manner in which it is to be performed, I declare that what I claim is:

1. A padlock comprising in combination, a body portion, a bow displaceable relative to said body portion and having one of its shanks journaled in the latter, said body portion having a bore perpendicular to said shank, a lock cylinder in said bore, a spring-influenced locking bolt for cooperating with

a shank of the bow and arranged parallel to said lock cylinder, a cam member for displacing the locking bolt upon a rotation of the lock cylinder, and means for maintaining the lock cylinder in locking position.

2. In a padlock, a body portion, a lock cylinder arranged in a bore formed in said body portion, said lock cylinder having a crown formed with an inclined face, a locking bolt actuated by the inclined face of said lock cylinder upon the rotation of said lock cylinder, a notched pin displaceably mounted in said lock cylinder, a cylinder locking pin mounted in said lock cylinder and engageable with said notched pin for locking said cylinder, said first mentioned pin being displaceable by the insertion of a key, substantially as and for the purpose described.
3. In a padlock, a body portion, a lock

cylinder arranged in a bore formed in said body portion, said lock cylinder having a crown formed with an inclined face, a locking bolt actuated by the inclined face of said lock cylinder upon the rotation of said lock cylinder, a notched pin displaceably mounted in said lock cylinder, a cylinder locking pin mounted in said lock cylinder and engageable with said notched pin for locking said cylinder, said first mentioned pin being displaceable by the insertion of a key, substantially as and for the purpose described, said crown having a shallow notch therein, said locking bolt engaging in said notch when in locking position.

Signed at Berlin, Germany this 5th day of February, 1924.

HEINRICH BIEMER.
